(57) **CLAIM**

The ornamental design for a monitoring camera, as shown and described.

DESCRIPTION

FIG. 1 is a perspective view of a first embodiment of a monitoring camera in accordance with our design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof; and,

FIG. 7 is a bottom plan view thereof;

FIG. 8 is a perspective view of a second embodiment of a monitoring camera in accordance with our design;

FIG. 9 is a top plan view thereof;

FIG. 10 is a front elevational view thereof;

FIG. 11 is a left side elevational view thereof;

FIG. 12 is a right side elevational view thereof;

FIG. 13 is a rear elevational view thereof; and,

FIG. 14 is a bottom plan view thereof;

The black, grey and white colors in the monitoring camera shown in FIGS. 8–14 form no part of the claimed design. The dot-dash boundary line shown in FIG. 14 and the fogged-out area of the monitoring camera enclosed by this boundary line forms no part of the claimed design.

1 Claim, 8 Drawing Sheets
